[57] ABSTRACT

A synergistic, biocidally active mixture comprises surface active amines and/or aminoacids and 2-alkyl-amino-6-aminopyridines.

5 Claims, No Drawings

BIOCIDAL PREPARATION

CROSS REFERENCE TO PRIOR DISCLOSURE

This invention corresponds to Disclosure Document 000737, deposited on Oct. 21, 1969.

FIELD OF INVENTION

The present invention relates to biocidal preparations which are characterized by comprising an effective amount of synergistic mixture of surface-active amines and/or aminoacids and 2-alkylamino-6-aminopyridines.

BACKGROUND INFORMATION AND PRIOR ART

A recently filed U.S. patent application Ser. No. 51,396, which is based on German Pat. application No. P 19 33 504.7, as well as U.S. Pat. application Ser. No. 10,280, filed Feb. 10, 1970 now U.S. Pat. No. 3,647,808, based on German application No. P 19 08 078.5, disclose synergistic mixtures which contain 2-alkylamino-6-aminopyridines as bacteriologically active component. The second component suggested in the applications referred to consists of quaternary ammonium compounds or betaines.

These previously disclosed mixtures or preparations made therefrom exhibit excellent bacteriological characteristics, characteristics which are also pronounced in the presence of soaps, protein or lipoids. However, the cleaning action and foam forming properties of preparations which contain quaternary ammonium compounds and 2-alkylamino-6-aminopyridines are not always satisfactory, particularly if strongly soiled materials are to be cleaned. For this reason additional ingredients, such as, for example, non-ionogenic tensides have to be incorporated into the preparations so as to improve the cleaning and foaming actions.

In respect to preparations which contain betaines, it will be appreciated that mixtures of 2-alkylamino-6-amino-pyridines and betaines are relatively expensive. This is so because the betaines which in themselves are relatively inexpensive and which are used in the mixture as solubilizing agent, do not themselves possess any bacteriological activity. For this reason, higher concentrations of active component have to be used which thus renders the preparation relatively expensive.

SUMMARY OF THE INVENTION

It is a primary object of the invention to overcome the drawbacks of the known synergistic mixtures and preparations and to provide a biocidally active mixture which has superior cleaning and foam producing characteristics, is relatively inexpensive and exhibits excellent biocidal or bacteriological properties.

Generally, it is an object of the invention to improve on the art of synergistic mixtures and preparations exhibiting biocidal activity.

Briefly, and in accordance with this invention, it has surprisingly been found that the above indicated objects are superiorly obtained and the drawbacks referred to are effectively overcome by synergistic mixtures which comprise surface active amines and/or aminoacids as well as 2-alkylamino-6-aminopyridines. Such mixtures, contrary to the individual components

taken alone, exhibit superior biocidal activity and excellent cleaning action over a wide pH range. Further, the inventive mixtures or preparations have satisfactory compatibility in respect to skin and mucous membranes and are substantially insensitive in respect to protein, lipoids and anionic detergents. Moreover, the inventive mixtures are exceedingly economical both in respect to manufacture and use.

Concerning the surface active amines, compounds of the following formula I yield excellent results:

In this formula, R¹ is alkyl with 8 to 18 carbon atoms, in which the carbon chain may be interrupted by —O—, —NH—, or

R² is hydrogen, —CH₃ or —CH₂CH₂OH, and R³ is hydrogen or —CH₂CH₂OH, —(CH₂CH₂NR²), —(CH₂CH₂NR²)_mR² or —(CH₂CH₂CH₂NR²)_mR², wherein m has a value of 1 or 2.

If a surface active aminoacid is used, compounds of the general formula II are recommended:

wherein R¹ and R² have the above meaning, and R⁴ is one of the groups

As 2-alkylamino-6-aminopyridines, compounds of the general formula III are used:

wherein R⁵ is alkyl with eight to 18 carbon atoms or the group

wherein X is chlorine or bromine. The preparation of compounds of formula III is disclosed in U.S. Pat. No. 3,647,808, column 2.

Surface active amines corresponding to and being embraced by formula I are, for example, laurylamine, N,N-bis-hydroxyethyl laurylamine, N-hydroxyethyl laurylamine, N,N-dimethyl laurylamine, N-lauryl-

rylethylenediamine, N-lauryl-diethylenetriamine, N-laurylpropylenediamine, N-lauryl-N', N'-dimethylpropylenediamine and N-lauryldipropylenetriamine, as well as the analogous compounds which instead of lauryl contain octyl, decyl, tetradecyl, hexadecyl or octadecyl. Particularly economical are often times mixtures of such homologues as they, for example, are formed in the production of surface active amines from natural fatty acids, such as, for example, coconut fatty acids.

Surface active aminoacids which can successfully be used for the purposes of this invention and are embraced by the formula II, are, for example, N-laurylaminooacetic acid, N-laurylethylenediaminoacetic acid, N-lauryldiethylenetriaminoacetic acid, N-laurylpropylenediaminoacetic acid, N-lauryl-diethylenetriamino- α -propionic acid and N-laurylpropylenediamino- β -butyric acid, as well as the homologue compounds wherein the lauryl group is replaced by octyl, decyl, tetradecyl, hexadecyl or octadecyl and their mixtures, for example, mixtures having alkyl which is derived from a coconut fatty acid.

The compounds of formula I and II may, in accordance with the invention, preferably be employed in the form of their mixtures. Such mixtures are, for example, obtained if compounds of formula I are reacted with chloroacetic acid, α -chloropropionic acid or crotonic acid in a mole ratio of $>1:1$. However, it is also feasible to employ the compounds of the formulas I and II individually, to wit, not in mixture, for the purpose of preparing the inventive preparations or mixtures which then additionally contain the 2-alkylamino-6-aminopyridines. However, in such event, it should be observed that not all the compounds of formula I are sufficiently water soluble at pH values of >7 . Accordingly, if the compounds of formula I are used without formula II compounds, surface active amines of sufficient water solubility at the indicated pH, should be used, such as, for example, N-hydroxyethyllaurylamine, lauryldiethylenetriamine, laurylpropylenediamine, lauryldipropylene-triamine and N-lauryl-N', N'-dimethylpropylenediamine.

Reverting now to the compounds corresponding to formula III, the following examples embraced by this formula are suitable: 2-octylamino-6-aminopyridine, 2-decylamino-6-aminopyridine, 2-laurylamino-6-aminopyridine, 2-myristylamino-6-aminopyridine, 2-stearylaminoo-6-aminopyridine, 2-p-chlorobenzylamino-6-aminopyridine and 2-o-chlorobenzylamino-6-aminopyridine.

The weight ratio of the substances of formula I and/or II to the substances of formula III should in the inventive mixtures or preparations be between about 5 : 1 and 1 : 3. A preferred ratio is between about 3 : 1 and 1 : 2.

The manufacture of the inventive preparations or mixtures is accomplished in technically exceedingly simple manner, by simply mixing the individual components per se or by mixing them in the form of their aqueous or alcoholic solutions at temperatures between about 20° to 100°C. In addition to water and ethylalcohol, the following solvents are eminently suitable for the indicated purpose: n-propylalcohol, isopropylalcohol, ethylglycol, ethyleneglycol, propyleneglycol (1,2), dioxane and glycol-

dimethylether. If desired, non-ionogenic tensides may be incorporated into the mixtures or preparations. The inventive mixtures or preparations may be produced in solid form, as pastes or in dissolved or dispersed form.

5 The addition of inert carrier materials, such as thickeners, inorganic salts, such as alkali metal phosphates, alkali metal silicates, alkali metal borates or urea, as well as aroma imparting compounds, is of course feasible and does not affect the scope of this invention.

10 The inventive preparations or mixtures may be used as disinfectants and preservatives in food processing plants, breweries, animal breeding establishments and hospitals. They are also effective algecides, fungicides and virucides.

15 The invention will now be described by several examples, it being understood that these examples are given by way of illustration and not by way of limitation, and that many changes may be effected without affecting in any way the scope and spirit of this invention as recited in the appended claims.

20 The following examples describe the preparation of the inventive mixtures:

25 EXAMPLE 1
30 50 parts by weight of 2-octylamino-6-aminopyridine are dissolved in 100 ccm of alcohol while heating to 50°C. 200 parts by weight of an aqueous solution of 25 percent concentration are then added which solution contains as active component the reaction product of a mixture of 1 mole of N-lauryldiethylenetriamine and 2 mole of N-laurylpropylenediamine with 2 mole of chloroacetic acid. The pH value of the system thus obtained was adjusted to 4.5 by adding acetic acid. A clear foaming preparation was obtained containing about 28 percent of active ingredient. The preparation could be diluted with water in any desired ratio.

35 40 EXAMPLE 2
40 10 parts by weight of 2-octylamino-6-aminopyridine are dissolved in a mixture of 30 parts by weight of n-propanol and 10 parts by weight of glacial acetic acid. 45 50 parts by weight of a 20 percent aqueous solution containing as active ingredient the reaction product of 2 mole of N-laurylpropylenediamine and 1 mole of chloroacetic acid are then added. A clear, foaming solution is obtained which can be diluted with water in any desired ratio and which contains about 20 percent of active ingredient.

55 EXAMPLE 3
55 20 parts by weight of N-lauryl-N', N'-dimethylpropylenediamine, 10 parts by weight of 2-laurylamino-6-aminopyridine, 30 parts by weight of glacial acetic acid and 40 parts of water were worked into a homogenous preparation under heating to 60°C. The 60 preparation contains 30 percent of active ingredient and can be diluted with water in any desired ratio. The preparation exhibits pronounced fungicidal activity.

65 EXAMPLE 4
65 50 parts by weight of N,N-bis-hydroxyethyllaurylamine, 20 parts by weight of 2-chlorobenzylamino-6-aminopyridine, 30 parts by weight of concentrated

hydrochloric acid, and 40 parts by weight of ethylglycol are homogenized under heating to 50°C. The resulting solution contains 50% of active ingredient and can be diluted with water.

EXAMPLE 5

100 parts by weight of N-coconutalkylpropylene-diaminoacetic acid and 40 parts by weight of 2-decylamino-6-aminopyridine were dissolved in 300 parts by weight of propyleneglycol (1,2) under slight heating. The N-coconutalkylpropylenediaminoacetic acid was obtained by reaction of 1 mole of N-coconutpropylenediamine with 1 mole of chloroacetic acid. The chain length distribution in the coconut-propylenediamine was as follows:

C ₈ :	1.3 %
C ₁₀ :	4.5 %
C ₁₂ :	61.2 %
C ₁₄ :	30.3 %
C ₁₆ :	2.0 %
C ₁₈ :	0.7 %

20 After addition of 120 parts by weight of acetic acid of 30 percent concentration, a clear foaming solution containing 25 percent of active ingredient was obtained.

EXAMPLE 6

In a manner analogous to that of Example 5, a 30 preparation was manufactured which instead of N-coconutalkylpropylenediaminoacetic acid contained N-coconutalkylpropylenediamino- α -butyric acid. The latter was synthesized by reaction of N-coconutpropylenediamine with crotonic acid.

35 In order to demonstrate the synergistic effect of the inventive preparations, the bacteriological activity that the individual components of the mixtures.

The bacteriological tests were performed according to the "Richtlinien der deutschen Gesellschaft fuer Hygiene und Mikrobiologie (guidelines of the German association for hygiene and microbiology)".

TEST SERIES I

40 I a) Testing of the inventive preparation corresponding to Example 1:

The preparation consists of 1 part by weight of the reaction product of a mixture of 2 mole of C₁₂H₂₅NH-(CH₂)₃-NH₂ and 1 mole of C₁₂H₂₅NH-(CH₂)₂-NH-(CH₂)₂-NH₂ with 2 mole of chloroacetic acid and 1 part by weight of

This preparation is being designated as preparation A.

The pH of the 0.1 percent solution — calculated on 60 the total amount of active ingredient — was adjusted to a value of 5.

Species	Concentration of active substance in %	Action time in minutes
	1 2 5 10 20 30	

Staphylococcus aureus	0.1	-----
	0.05	-----
	0.01	-----
	0.005	++ - - -
	0.001	++ + + - -

Pseudomonas aeruginosa	0.1	-----

	0.05	-----
	0.01	-----
	0.005	++ + + - -
	0.001	++ + + + +

— = no bacteria growth
+ = bacteria growth

I (b) Control test with mixture outside the scope of this invention:

The bacteriological activity of the reaction product of a mixture of 2 mole of C₁₂H₂₅NH-(CH₂)₃-NH₂ and 1 mole of C₁₂H₂₅NH-(CH₂)₂-NH-(CH₂)₂-NH₂ with 2 mole of chloroacetic acid was examined (hereinafter referred to as preparation B). The pH of the solution containing 0.1 percent of active ingredient was adjusted to a value of 5. This was effected with acetic acid.

Species	Concentration of active substance in %	Action time in minutes
	1 2 5 10 20 30	

Staphylococcus aureus	0.1	-----
	0.05	++ - - -
	0.01	++ - - -

	0.001	++ + + + -

Pseudomonas aeruginosa	0.1	-----
	0.05	-----
	0.01	++ - - -
	0.005	++ + + - -
	0.001	++ + + + +

Proteus vulgaris	0.1	++ - - -
	0.05	++ - - -
	0.01	++ + - -
	0.005	++ + + - -
	0.001	++ + + + +

Escherichia coli	0.1	++ - - -
	0.05	++ - - -
	0.01	++ + - -
	0.005	++ + + - -
	0.001	++ + + + +

I (c) Control test with preparation outside the scope of this invention:

The bacteriological activity of a dispersion of 2-ocetylaminopyridine was tested (hereinafter referred to as preparation C).

The pH value of the 1 percent dispersion was adjusted to a value of 4.3 with acetic acid.

Species	Concentration of active substance in %	Action time in minutes
		1 2 5 10 20 30
<i>Staphylococcus aureus</i>	0.1	— — — — —
	0.05	++ — — — —
	0.01	++ + — — —
	0.005	++ + + + +
<i>Pseudomonas aeruginosa</i>	0.1	— — — — —
	0.05	++ — — — —
	0.01	++ + — — —
	0.005	++ + + + +
<i>Proteus vulgaris</i>	0.1	— — — — —
	0.05	++ — — — —
	0.01	++ + — — —
	0.005	++ + + + +
<i>Escherichia coli</i>	0.1	— — — — —
	0.05	— — — — —
	0.01	++ — — — —
	0.005	++ + + + +

Comparison of the values of Tables Ia through Ic indicates clearly the superiority of the inventive synergistic mixture (preparation A) as compared to the individual components (preparations B and C).

TEST SERIES II

II (a) Test of an inventive preparation corresponding to Example 2:

The preparation consists of 1 part by weight of the reaction product of 2 mole of $C_{12}H_{25}NH-(CH_2)_3-$ NH_2 with 1 mole of chloroacetic acid and 1 part by weight of

This preparation is indicated as preparation D.

The pH of an aqueous solution containing 0.1% of active ingredient was adjusted with acetic acid to a value of 5.

Species	Concentration of active sub- stance in %	Action time in minutes					
		1	2	5	10	20	30
Staphylo- coccus aureus	0.1	—	—	—	—	—	—
	0.05	—	—	—	—	—	—

		0.001	++ + + + +

20 II (b) Control test outside the scope of the invention:
The bacteriological activity of the reaction product
of 2 mole of $C_{12}H_{25}NH-(CH_2)_3-NH_2$ with 1 mole of
chloroacetic acid was tested (preparation E).

25 The pH of the solution containing 0.1 percent of ac-
tive ingredient was adjusted with acetic acid to a value
of 5.

Species	Concentration of active sub- stance in %	Action time in minutes
30		1 2 5 10 20 30
Staphylo- coccus	0.1	+-+- - - -
aureus	0.05	++ - - - -
	0.01	++ + - - -
	0.005	+++ + - - -
	0.001	+++ + + + +

		0.001	+++ + + + +

The comparison of the values of Tables II (a) and II (b) indicates clearly the superiority of the inventive mixture as compared to the characteristics of the individual components.

TEST SERIES III

In this test series, the bacteriological activity of the inventive preparations A and D, as well as of the control preparations B and E is tested in the presence of 20 percent by weight of bovine (cattle) serum. The tests were also performed pursuant to the Richtlinien der deutschen Gesellschaft fuer Hygiene und Mikrobiologie.

The pH of an aqueous solution containing 0.1 percent of active ingredient amounted to a value of 5.

III (a) Bacteriological activity of the inventive preparations A and D in the presence of 20 percent by weight of bovine serum.

The average value whose numerical value is a measure for the irritation effect is significantly lower in the inventive preparations A and D than in the comparison preparations B and E. It follows that the inventive preparations cause considerably less irritation effect than the control preparations.

What is claimed is:

1. A synergistic biocidal mixture consisting essentially of

a. a compound of the formula

wherein R¹ is alkyl with eight to 18 carbon atoms, R² is hydrogen, —CH₃ or —CH₂CH₂OH, and R³ is hydrogen, —CH₂CH₂OH, —(CH₂CH₂NR²), —(CH₂CH₂NR²)_mR², —(CH₂CH₂CH₂NR²)_mR², m having a value of 1 or 2, —CH₂COOH,

—CH₂CH₂NHCH₂COOH, —CH₂CH₂NHCH₂CH₂NHCH₂COOH or —CH₂CH₂CH₂NHCH₂COOH, and b. 2-alkylamino-6-aminopyridines of the formula:

wherein R⁵ is alkyl of eight to 18 carbon atoms or the group

20

wherein X is chlorine or bromine, the weight ratio a : b being about between 5 : 1 to 1 : 3.

2. A mixture as claimed in claim 1, wherein the weight ratio of a : b is between about 3 : 1 to 1 : 2.

3. A biocidal preparation essentially consisting of a biocidally effective amount of the synergistic mixture of claim 1 and an inert carrier.

4. A preparation as claimed in claim 3, wherein said inert carrier is water, a lower alkanol, a lower alkylene glycol, dioxane or glycoldimethylether.

5. A preparation as claimed in claim 3, wherein the concentration of the active ingredient is between about 0.001 and 0.5 percent.

UNITED STATES PATENT OFFICE
CERTIFICATE OF CORRECTION

Patent No. 3,717,579 Dated February 20, 1973

Inventor(s) Eberhard Hofmann and Ulrich Holtschmidt

It is certified that error appears in the above-identified patent and that said Letters Patent are hereby corrected as shown below:

In the heading of the patent insert:

-- [30] Foreign Application Priority Data

October 10, 1969 Germany.....P 19 51 156.9-41--

Signed and sealed this 3rd day of July 1973.
